METHOD OF MAKING TOILET SEATS

Hippolyte W. Romanoff, New York, N. Y., assignor
to Alexander Schwartz, New York, N. Y.

Application December 7, 1939, Serial No. 308,019

6 Claims. (Cl. 4—237)

My invention relates to methods of making toilet seats and has particular reference to methods of making toilet seats, toilet covers and similar articles from corrugated paper.

5 This is a continuation-in-part of my application Serial No. 272,946, filed May 11, 1939, which matured into Patent No. 2,185,169.

My invention has for its object to provide a method of making toilet seats and covers by 10 winding a strip of a corrugated paper on a mandrel and cementing together the successive turns. I prefer to use for this purpose corrugated paper comprising a corrugated strip to one side of which a flat sheet of paper is glued, the strip being so cut that the corrugations extend straight across from one edge of the strip to the other. Such a strip is very flexible, so that it can be wound into a tight roll following the shape of the mandrel. The article thus obtained is very 15 light in weight, a large portion of its volume representing air spaces between the corrugations. At the same time it is very strong, resisting compression, since the corrugations extend directly across from one side of the article to the other, being highly resistant to compression. The successive turns may be glued together during the 20 process of winding or they may be secured together upon completion of the winding by applying glue to the sides of the article, thereby 25 gluing together the edges of the strip. The edges of the article can then be rounded off by grinding or other suitable mechanical process. The finally shaped article can be given smooth appearance by applying a layer of a suitable plastic compound, such as plastic wood, to the outer surface of the article, so as to fill the spaces between the corrugations at the surface, leaving air spaces inside the article. The surface of the article can then be polished smooth and painted 30 with a suitable water-resisting paint or enamel.

Articles made by my method are very light, inexpensive and possess relatively great rigidity. They are superior to ordinary seats made of wood in that they do not warp, do not crack, and retain 35 their shape after long usage. They can be refinished and re-enameled from time to time.

The outer contour or shape of the article can be controlled by placing suitable inserts between the turns of the strip as described in my foregoing patent application. These inserts can be also used for attaching hinges by suitable bolts or screws. Instead of polishing or painting the outer surface of the article, a moulded cover may be cemented on the outside, as also described in 50 my foregoing application.

As a modification of my method, the article, upon completion of the winding of the strip and while the glue is still wet, may be pressed out to provide a convex surface at one side. The 55 other side can be then ground or trimmed flat.

Another modification of my method as described in my foregoing patent application, consists in winding a long cylindrical body on a suitable mandrel, using for this purpose a wide sheet of corrugated paper with corrugations extending lengthwise of the mandrel. Inserts, if such are required, may be provided in the form of long strips or bars inserted between the turns at suitable points. The cylindrical body, upon completion of winding, is then cut by suitable 10 gang cutters or saws into a plurality of relatively thin boards which are then finished into toilet seats or seat covers.

My invention is more fully described in the accompanying specification and drawing in 15 which:

Fig. 1 is a top plan view partly in section of a seat made by my method;

Fig. 2 is an enlarged sectional view taken on the line 2—2 of Fig. 1; 20

Fig. 3 is a fractional sectional view of a modified construction of the seat;

Fig. 4 is a top plan view of a seat of a modified construction;

Fig. 5 is a top plan view partly in section of a 25 seat cover made by my method;

Fig. 6 is a sectional view of a seat of a modified construction;

Fig. 7 is an enlarged detail view of the seat showing filling at the surface; 30

Fig. 8 is a perspective view of a cylindrical body wound by my method and ready to be cut into a plurality of seats;

Fig. 9 is a diagrammatic view showing the cylindrical body in position to be cut by circular 35 saws into separate seats;

Fig. 10 is a perspective view showing my method of making seats.

My improved method of making toilet seats and similar articles consists in winding a strip 40 of corrugated paper around a suitable mandrel 1 as shown in Fig. 10. The corrugated paper preferably consists of a corrugated strip 2 glued at one side to a flat strip 3 so that it retains its longitudinal flexibility, being at the same time 45 fully rigid in transverse direction, the corrugations being aligned transversely to the strip. The successive turns of the corrugated paper strip are held together as by applying glue to the flat side of one turn and pressing against it the tops 50 of corrugations of the other turn until the complete seat 4 is formed.

The seat can be also wound without application of the glue until the winding is completed, and then glue is applied only to the top and bottom surfaces of the seat at the edges of the strip. 55

The peripheral contour of the seat can be made of any desired shape by placing inserts or filling pieces 5 between the turns as shown in Figs. 1 and 2. With such inserts a flat rear side 60

can be obtained for mounting hinges which support the seat on a toilet bowl (not shown). Additional inserts 6 may be provided for bolts or screws 7 which fasten hinges 8 (Fig. 3) to the seat. The inserts 6 are preferably placed when the seat is fully formed, by drilling a corresponding hole edgewise through the seat and cementing the insert in the hole. The inserts are preferably made of a machinable material, such as wood, fiber, etc., or they can be made of pieces of corrugated board.

Another method of making toilet seats is shown in Fig. 4. The seat 9 is wound to a larger overall size as shown in dotted lines 10. The excess material is afterwards removed by trimming or grinding.

The covers 11, Fig. 5, are formed in a similar manner by winding a strip around an elongated mandrel or core 12. The core in this case is not removed upon completion of the winding, as is the case with the seat, but is left in the cover, being firmly cemented in its place. It is also possible to wind the cover without any core, using the first turns of the strip as the core.

25 The seat, when fully wound, is ground or trimmed around so as to round off its corners as shown in Figs. 2 and 3. A smooth moulded cap or cover 13 may be cemented to the outside of the seat for making it smooth and impervious to water, a similar flat cover 14 being cemented to the under side of the seat.

30 The seat can be also finished smooth without the additional covers by closing the opening between the corrugations with a suitable plastic or cementitious plastic material 15, Fig. 7. The plastic material penetrates only at the surface, leaving air spaces between the corrugations inside the seat.

35 These air spaces render the seat very light in weight, the necessary strength being provided by the straight corrugations extending across the thickness of the seat. The surfaces of the seat are ground and polished when the plastic material becomes sufficiently hardened. A coat of paint or enamel can be then applied to the polished surface, if desired.

40 Another method of finishing the seat is shown in Fig. 6. The seat, upon winding and before the glue or plastic material is hardened, is formed in a special mould, so that its upper side is made convex as shown. The seat may be left in the mould until the plastic or cementitious material is hardened. Upon removal from the mould, the seat is ground flat on the under side.

45 Another method is shown in Figs. 8 and 9, especially applicable to a mass production. A wide sheet 16 of corrugated board is wound on a long mandrel or core 17, the latter being mounted on a shaft 18 for its rotation. Long inserts 19 are placed between the layers of the sheet to form corners of the seats. The completed article in the form of an elongated cylinder 20 is cut into a number of separate seats by means of circular saws 21 mounted on a shaft 22.

50 For splitting the board or wound cylinder 22 a gang saw can be used, either on a reciprocating frame or in the form of a continuous zig-zag mounted band saw.

55 It is understood that my invention may be further modified without departing from the spirit of the invention, as set forth in the appended claims.

I claim as my invention:

1. A method of making a toilet seat consisting 75 in tightly winding around a mandrel a strip of

corrugated paper having a strip of flat paper glued to one side with the corrugations extending straight across the strip, the width of the paper being substantially equal to the thickness of the finished article, gluing the successive turns together, placing filling pieces between the corrugations extending to the edges of the product so as to control the outer contour of the product, and finally grinding the surfaces to the required shape and finish.

2. A method of making a toilet seat consisting in tightly winding around a mandrel a strip of corrugated paper having a strip of flat paper glued to one side with the corrugations extending straight across the strip, the width of the paper being substantially equal to the thickness of the finished article, the tops of the corrugations of one turn being during the process of winding glued to the flat paper of the other turn, the corrugations forming transverse air ducts in the product, grinding the finished article to the required shape, filling the spaces between the corrugations at the surfaces of the article with a plastic material, partly entering the ducts, finishing the article on all sides and covering with a layer of waterproof material.

3. A step in the method of making toilet seats consisting in tightly winding side by side a strip of a corrugated paper having a strip of flat paper glued to its one side with straight corrugations extending across the strip, gluing together the tops of the corrugations of one turn to the flat paper of the other turn, the corrugations forming transverse air ducts in the product, and closing the ends of the air ducts at the surface of the product with a plastic material partly entering the ducts.

4. A method of making toilet seats consisting in forming an elongated body by winding a strip of fibrous material, placing inserts in the form of long bars between the turns of the strip so as to control the shape of the outer contour of the body, splitting the body with the inserts into a plurality of boards of a desired thickness, cementing together the successive turns of the strip, rounding off the upper corners of each seat, and rendering the surfaces of the core smooth and water-tight.

5. A method of making a toilet seat consisting in tightly winding around a mandrel a strip of corrugated paper having a strip of flat paper glued to one side with the corrugations extending straight across the strip, the width of the paper being substantially equal to the thickness of the finished article, adding sufficient number of turns at the periphery of the article as required for the widest portions of the article, gluing together the consecutive turns, removing portions of the added turns at the periphery of the article for imparting the desired contour thereto, rounding the upper corners, and covering the surface with a layer of water-proof material.

6. A method of making a toilet seat consisting in tightly winding around a mandrel a strip of corrugated paper having a strip of flat paper glued to one side with the corrugations extending straight across the strip, the width of the paper being substantially equal to the thickness of the finished article, gluing the successive turns together, boring holes edgewise through the product across the corrugations, and placing inserts into the holes adapted to receive screws for hinges.
